UNITED STATES PATENT OFFICE

2,532,079

SAFETY ELECTRICAL CONTROL FOR
DRILLING MACHINESJohn S. Beltz, Columbus, Ohio, assignor to The
Jeffrey Manufacturing Company, a corporation
of Ohio

Application October 11, 1947, Serial No. 779,383

7 Claims. (Cl. 255—51)

1

This invention relates to a drilling machine, and an object of the invention is to provide improved electrical remote control means for a drilling machine.

Another object of the invention is to provide a drilling machine in which an electric motor drives the truck or main frame thereof through traction means and also drives the pump of a hydraulic system for adjusting drilling mechanism mounted on a boom, there being disengageable drive gearing between the electric motor and the traction means of the truck or main frame which will disable the electric circuit for the driving motor and/or for the motor of the drilling mechanism whenever the disengageable gearing is in its engaged position, thereby precluding accidental driving of the traction mechanism simultaneously with operation of the drill.

Another object of the invention is to provide apparatus of the above mentioned character in which the driving motor for the truck or main frame also drives a hydraulic pump which is part of a hydraulic system for adjusting the drill mechanism through hydraulic motors carried by said drill mechanism.

Still another object of the invention is to provide apparatus having the above mentioned characteristics in which the drill mechanism is mounted on a boom which extends beyond the machine truck or main frame and in which control switches, such as push buttons, are carried by the boom for controlling the electrical system.

Other objects of the invention will appear hereinafter, the novel features and combinations thereof being set forth in the appended claims.

In the accompanying drawings:

Fig. 1 is a side elevational view of a drilling machine incorporating the features of my invention, certain parts being omitted;

Fig. 2 is a plan view of said machine;

Fig. 3 is an electrical wiring diagram of the machine; and

Fig. 4 is an enlarged sectional view showing part of the disengageable drive gearing and associated control switch.

The drilling machine herein disclosed follows the construction disclosed in more detail in my application Serial No. 769,358, entitled Power-Driven and Controlled Coal Mine Drilling Machine, filed August 19, 1947.

As shown particularly in Figs. 1 and 2 of the drawings the drilling machine includes a truck comprising a main frame 10 mounted on traction means which is illustrated in the form of traction wheels 11, there being a pair of said wheels

at each end of the main frame 10, said wheels being adapted to ride on rails, one of which is seen at 12. The main frame carries an electric motor 13 which is interconnected with the traction wheels 11 through a disengageable drive gearing 14, parts of which are illustrated in detail in Fig. 4 of the drawings. Of particular significance, insofar as the invention herein claimed is concerned, is the fact that drive gearing 14 includes a jaw clutch 15 provided with an operating lever 16 which may be operated to effect a driving or non-driving relation between the motor 13 and traction wheels 11.

The operating lever 16 carries a cam 17 which controls a switch 18 of the electric circuit hereinafter described in detail. The arrangement of parts is such that whenever the clutch 15 is engaged switch 18 is open, and when it is disengaged said switch is closed. In Fig. 4 of the drawings the clutch 15 is illustrated in its disengaged position and cam 17 has actuated switch 18 to its closed position. The opposite relation between the cam 17 and switch 18 is illustrated in Fig. 3 of the drawings in which the clutch 15 is engaged.

Pivottally mounted for swinging movement about an upright axis is a substantially horizontally extending boom 19 which extends appreciably beyond the main frame or truck 10. This boom may be swung to various positions by hydraulic motor mechanism 20 which is disclosed in detail in my application Serial No. 769,358. Adjacent its outer end the boom 19 carries a drill mechanism 21 which is also disclosed in detail in my application Serial No. 769,358. It is sufficient to point out that said drill mechanism 21 includes an electric motor 22 (see Fig. 3) mounted in a motor housing 23 and that said drill mechanism 21 includes various adjusting devices each operated by a hydraulic motor. For example, the drilling mechanism 21 may be swung about a vertical or upright axis by drive mechanism including hydraulic motor 24. The drill may be raised and lowered by hydraulic cylinder type motors 25. In addition, a hydraulic motor 26 is provided to swing the drill mechanism about the longitudinal axis of a supporting neck 27.

The hydraulic system which includes the hydraulic motors 24, 25 and 26 also includes a pump 28 which is directly and permanently connected to the electric motor 13. Control valves, designated generally by the reference character 29, provide for control of the various hydraulic motors 24, 25 and 26 as well as the hydraulic motor 20, all of which are disclosed com-

pletely in my application Serial No. 769,358. Each of these hydraulic motors provides some control or adjustment for the drilling mechanism, as determined by the operator who may control any one of the four individually operable levers of the valve mechanism 29.

The main driving motor 13 is provided with the usual manually operated controller 30 provided with the usual reversing mechanism 31. In addition, said motor 13 is provided with a remote control mechanism so that the operator may stand adjacent the hydraulic control valves 29 and control the starting and stopping of both the main electric motor 13 and the drill motor 22. To this end a pair of push button type switches 32 and 33 (see Fig. 3) are mounted in a housing 34 (see Figs. 1 and 2), carried on the boom 19 adjacent the operator's position near the control valves 29, thus providing for the remote control particularly of the motor 13.

As a safety feature it is desirable to de-energize or disable the remotely controlled electrical control system or circuit whenever the gearing connects the main motor 13 with the traction wheels 11, and to energize said system only when this drive gearing is disengaged. This makes it impossible for the operator inadvertently to drive the traction wheels while the drilling mechanism is being operated or is being adjusted, the adjustment of the mechanism, of course, being through the hydraulic system controlled by pump 28 and driven by motor 13, the actual drilling, of course, being through operation of motor 22.

Attention is now directed particularly to Fig. 3 of the drawings and to the control system for the electric motors 13 and 22. The drum type controller 30 and reversing switch 31 are of standard construction and need no detailed description. Assume, for example, the reversing switch 31 is so positioned that the two end pair of upper or stationary contacts are bridged and that controller 30 is moved to its first position, the motor 13 will be energized by connecting the positive line 35 through the first stationary contact of controller 30 and through the interconnected drum contacts to the last stationary contact, thence to a shunt field coil 36 which is connected directly to the negative line 37. The armature circuit for the motor 13 can be traced through the right-hand stationary contact of controller 30 which is now connected to positive, as above described, through conductor 38, resistor 39, the second right-hand stationary contact of controller 30, over conductor 40 and to the second contact from the right of the top row of four contacts (stationary) of reversing mechanism 31 through a bridging contactor of reversing switch 31 to one side of the armature of motor 13 over conductor 41, the circuit extending by way of conductor 42 to the third stationary contact of the reversing mechanism 31 through a bridging contactor to the last or left-hand stationary contact thereof, thence by conductor 43 to the negative line 37 through series winding 44. Operation of the controller handle and drum to successive positions successively removes segments of the resistor 39 in a standard manner.

This manual control of the motor 13 is normally effected with the drive gearing 14 in driving relation to the traction means 11 so as to propel the complete drilling machine and effect its movement from one place to another.

After the drilling machine has been driven or

transported to a desired position it is necessary for the operator to disengage the clutch 15 by actuating lever 16 before he can start the drill motor 22 or remotely control the main motor 13.

6 The main motor 13 in effect takes the place of two motors. That is, it is used to propel or transport the entire drilling machine, and when the drilling machine is standing still and the drive gearing for the traction means disengaged it merely acts to drive the pump 28 of the hydraulic system. Obviously, if desired, within the broad scope of my invention, separate motors may be employed for the traction function and for driving the pump 28. In the preferred embodiment, however, the motor 13 serves its double function above described.

Assuming that the drilling machine has been positioned to drill a hole, for example, in the face of a coal mine room, the operator will take his 20 place adjacent the hydraulic valve 29 and the push button switches 32 and 33 in the housing 34. In this position he can effect the above described adjustments of the drilling machine 21 as well as swinging of the boom 19 by the hydraulic motor mechanism 20 which is also controlled by one of the valves 29 and is supplied with fluid from the pump 28. This, of course, is employed to adjust the position of the drill 21 in one of its possible adjustments.

If the operator should fail to disengage the clutch 15 he will not close the switch 18 of the remote control electrical system and consequently he will disable said remote control system, making it impossible for him to start either the motor 13 or the motor 22 from his position adjacent the boom 19. Assuming, however, that he has so disengaged the driving connection to the traction wheels and switch 18 is closed, it is possible for him to energize either motor 13 or motor 22, or both of them, the first for the purpose of driving the pump 28 to develop hydraulic fluid under pressure to effect adjustment of the drilling mechanism as above described, the second to start the driving electric motor 22 which actually turns the auger or bit of the drilling mechanism. For example, to start the motor 13 by remote control the operator will close the push button switch 32 and hold it closed. When this is done the positive conductor 35 is extended through the switch 18 and through switch 32 to energize the solenoid of relay 45, one terminal of which is permanently connected to the negative line 37. Relay 45 on energizing closes its contacts, thereby connecting line 35 with the right-hand end of resistor 39 or, in other words, with conductor 38, which has exactly the same effect as moving the controller 30 to its first position. This will start the motor 13 with the resistor 39 in series with the series winding 44 over the circuit above described, extending from resistor 38 and continuing to the negative line.

Shunt field 36 will also be connected across the lines 35 and 37 through this contact and through conductor 38. This will start the motor 13 in rotation. Switch 32 also closes the circuit over a branch conductor 46, negative coefficient of resistor 47 to the solenoid of a relay 48, one terminal of which is permanently connected to negative conductor 37. The resistance 47 is such that when this circuit is first energized its resistance is so high that relay 48 is not immediately actuated but as the current flows through it its resistance progressively decreases until after a predetermined time relay 48 will be energized. When

this happens the lower contact thereof closes an obvious circuit to shunt the resistor 41, and the upper contact closes a circuit which shunts out resistor 39 entirely. This shunt circuit extends from the right-hand end of resistor 39 over conductors 49 and 50, the latter leading to the second stationary contact of controller 30 which is directly connected to the second stationary contact of the upper row of stationary contacts of reversing switch 31. In other words, the first and second contacts of the controller 30 are directly connected together over conductors 38, 49 and 50 which obviously has exactly the same result as moving the controller drum 30 into its fourth position.

Push button 33 controls relay 51 over an obvious circuit since one terminal of its solenoid is connected to negative line 37, the other through switch 33 and switch 18 to positive line 35. When relay 51 is energized it closes the circuit to the drill motor 22 over conductor 52 which leads to positive line 35, the other side of the motor 22 being directly connected to negative connector 37.

Normally only one of the push buttons 32, 33 will be operated because it is normally desirable first to position the drilling mechanism and then when positioned to operate its driving motor to drill a hole. Also the switches 32 and 33 are preferably push button type, making it impossible for the operator to leave his position while the mechanism is running. It is obvious, however, that within certain broad aspects of the invention either or both of these switches 32 or 33 may be snap switches, or the like, which will remain closed.

It is further obvious from the above traced circuits that whenever the driving connection is effected between the motor 13 and the wheels 11, switch 18 will open the circuits leading to relays 45, 48 and 51.

Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of my invention, what I desire to secure by Letters Patent of the United States is:

1. A drilling machine including a main frame, traction means for propelling said main frame, a driving motor for said main frame, disengageable gearing interconnecting said motor and traction means, a boom carried by said main frame and extending therefrom, drilling mechanism mounted on said boom, a hydraulic system for controlling said drilling mechanism including a pump directly connected to said driving motor and a hydraulic motor for operating said drilling mechanism, and control means for starting and stopping said driving motor including a switch operable to disable said control means when said disengageable gearing is engaged, said control means also including switch means located on said boom for starting said driving motor.

2. A drilling machine including a main frame, traction means for propelling said main frame, a driving motor for said main frame, disengageable gearing interconnecting said motor and traction means, a boom carried by said main frame and extending therefrom, drilling mechanism mounted on said boom, a hydraulic system for controlling said drilling mechanism including

a pump directly connected to said driving motor and a hydraulic motor for operating said drilling mechanism, and control means for starting and stopping said driving motor including a switch operable to disable said control means when said disengageable gearing is engaged, said control means also including switch means located near said drilling mechanism for starting said driving motor.

3. A drilling machine including a frame, traction means therefor, means for driving said traction means including an electric motor on said frame, disengageable drive gearing interconnecting said traction means and said motor, a boom carried by and extending beyond said frame, drill mechanism carried by said boom, said drill mechanism including an electric driving motor, hydraulic mechanism for adjusting said drill mechanism including a pump driven by said first named electric motor and hydraulic motor means for said drill mechanism, and an electrical control system for said two electric motors including a switch operable by said disengageable drive gearing for disabling said system and separate switch means for said motors mounted on said boom.

4. A drilling machine including a frame, traction means therefor, means for driving said traction means including an electric motor on said frame, disengageable drive gearing interconnecting said traction means and said motor, a boom carried by and extending beyond said frame, drill mechanism carried by said boom, said drill mechanism including an electric driving motor, hydraulic mechanism for adjusting said drill mechanism including a pump driven by said first named electric motor and hydraulic motor means for said drill mechanism, and an electrical control system for said two electric motors including a switch operable by said disengageable drive gearing for disabling said system and separate switch means for said motors.

5. A drilling machine including a frame, traction means therefor, means for driving said traction means including an electric motor on said frame, disengageable drive gearing interconnecting said traction means and said motor, a boom carried by and extending beyond said frame, drill mechanism carried by said boom, said drill mechanism including an electric driving motor, and an electrical control system for said two electric motors including a switch operable by said disengageable drive gearing for disabling said system and separate switch means for said motors mounted on said boom.

6. A drilling machine including a frame, traction means therefor, means for driving said traction means including an electric motor on said frame, disengageable drive gearing interconnecting said traction means and said motor, a boom carried by and extending beyond said frame, drill mechanism carried by said boom, said drill mechanism including an electric driving motor, and an electrical control system for said two electric motors including a switch operable by said disengageable drive gearing for disabling said system and a switch for said drill mechanism electric motor mounted on said boom.

7. A drilling machine including a frame, traction means therefor, means for driving said traction means including an electric motor on said frame, disengageable drive gearing interconnecting said traction means and said motor, a boom carried by and extending beyond said frame, drill mechanism carried by said boom, said drill mechanism including an electric driving motor, and an

electrical control system for said two electric motors including a switch operable by said disengageable drive gearing for disabling said system and a switch for said drill mechanism electric motor.
